UNITED STATES PATENT OFFICE.

HARRY E. CAMPBELL, OF MILWAUKEE, WISCONSIN, ASSIGNOR TO UNION ELECTRIC MANUFACTURING COMPANY, OF MILWAUKEE, WISCONSIN, A CORPORATION OF WISCONSIN.

ELECTRIC CONTROLLER.

Application filed November 27, 1922. Serial No. 603,613.

This invention relates to electric controllers and more particularly to the constructional arrangement of an electric controller particularly adapted for use in mines or other similar places where combustible gaseous zones are encountered.

One of the features of the invention is the particular construction and arrangement of the casing wherein a gas-tight chamber is provided so that in the event an arcing of the contacts occur no flame or burning material can escape from the interior of the casing thus eliminating the possibility of explosions.

Another feature of the invention resides in the construction of the door for closing the casing whereby a gas-tight joint between the door and casing is established and the door secured or released with facility.

Another important feature of this invention resides in the construction whereby electrical connection may be made with the contacts at the exterior of the casing.

Another important feature of construction resides in the provision of grooves on the controlling shafts and on the portion of the door which engages the casing thereby providing expansion and cooling chambers for any flaming gas which may escape through these points.

The novel combination, construction and arrangement of parts, wherein the features of this invention are efficiently accomplished will be made more apparent as the description proceeds, especially when considered in connection with the accompanying drawings wherein:

Fig. 1 is an elevation of a controller constructed in accordance with this invention, certain parts being broken away,

Fig. 2 is a side elevation of the controller,

Fig. 3 is a fragmentary elevational view showing a detail of construction,

Fig. 4 is a top plan view,

Fig. 5 is a fragmentary sectional view,

Fig. 6 is a horizontal section taken on the plane indicated by line 6-6 in Fig. 1, and

Fig. 7 is a similar view taken on the plane indicated by line 7-7 in Fig. 1.

Referring now to the drawings wherein like reference characters indicate like parts the novel combination and construction will be described, a detailed description of the

controller parts and circuit being omitted inasmuch as they form no important part of this invention.

The controller consists mainly of a casing 10 within which are housed the controller parts and through which passes the controller shafts 11 and 12. A controller handle 13 is secured to the main controller shaft and an operating handle 14 to the other controlling or reversing shaft.

The main casing 10 is open at one side thereof which open side is closed by a cover 15 or door 15 formed preferably with a flanged portion 16 which engages a flange 17 formed on the casing. The door and casing are formed with cooperating lugs so that the door may be hinged to the casing as indicated at 18.

For locking the door in place there is provided a plurality of locking clips 19 which are hook shaped and are each provided adjacent one of their ends with a beveled or inclined surface 20 adapted to engage a ledge or rib 21 formed on the casing 10. The other end of each locking clip 19 lies substantially in a parallel plane with the door or cover 15 and is slotted as indicated at 22. A bolt 23 passes through the slot of each clip 19 and into the cover 15 so that the clips 19 are displaceably and slidably mounted on the cover 15, these locking clips being movable a distance corresponding to the length of the slots 22.

Horizontal members 24 arranged on both sides of the door engage the clips 19 for horizontally displacing the same, this displacement taking place by reason of an actuating or locking bolt 25 which screw-threadedly engages nuts 26, which engage recesses 27 formed in enlargements 28 on the members 24. An operating handle 29 is keyed to the locking shaft 25 so that this shaft may be rotated and the pitch of the screw-threads is such that as the shaft is rotated the members 24 will either be moved toward or from one another and will consequently cause an engagement or disengagement of the locking clips 19 with the ledge 21 of the casing 10. In this manner all four locking clips 19 are caused to simultaneously engage the casing and with a uniform pressure so that the cover 15 may be firmly clamped in place.

The electrical circuit of the controller in-

cludes a blow-out coil 30 and contact switches 31 which are mounted on the cover 15 in such a position that when the cover 15 is closed the circuit will be completed. However, 5 when the cover 15 is removed the electrical circuit of the controller is opened and hence no arc or short circuit may occur which might ignite combustible gas in proximity to the controller.

10 The circuits of the controller includes a plurality of contacts 32 which extend through the casing and have terminals 33 arranged on the exterior of the casing 10 so that electrical connection therewith may be facilitated. For enclosing the electrical connection with these contacts there is provided supplemental casings or housings 34 which are secured to the main housing by bolts 35. By this arrangement electrical 15 connections may be made or altered without opening the main casing.

The controller shafts 11 and 12 are each provided with a plurality of small grooves 36 which act as expansion and cooling chambers for any flaming gas which might tend to seep through and escape from the casing 10 at this point. Any flaming gases at this point are effectually cooled below the ignition point before emerging so that possibility 20 of the same igniting any combustible gases in proximity of the controller is eliminated.

Furthermore the flange 16 of the cover 15 is provided with a plurality of grooves 37 25 which act similarly to the grooves 36.

From the foregoing it will be apparent that there is provided a controller having a casing which is gas-tight to the extent that flaming gases cannot effectually escape. Furthermore, means are provided whereby the controller circuit is open when the casing is opened for the purpose of examining the interior thereof or replacing worn or broken parts. Means are furthermore provided 40 whereby electrical connection with the controller contacts may be made at the exterior of the main casing without necessitating the opening of the same.

Consistent with the desire for a gas-tight 45 container, means are provided whereby the

cover or door of the container may be securely clamped in its closed position, the door being clamped at spaced intervals simultaneously with an equalizing clamping pressure by the actuation of a single clamp- 55 ing bolt.

Various modifications may suggest themselves and to this end reservation is made to make such changes in the specific construction illustrated as may come within the 60 purview of the accompanying claims.

Having thus described the invention, what I claim is:

1. In an electric controller, a casing for the controller shaft and contacts, a door for said casing, locking clips having inclined faces carried by said door and engaging said casing at spaced points and a locking bolt operable to cause the inclined faces of said clips to simultaneously engage said casing 70 to clampingly secure said door in closed position.

2. In an electric controller, a casing, a door having a gas-tight connection with said casing, locking clips having inclined faces slidably mounted on said door at spaced points about its edge and adapted to engage said casing for locking said door in closed position and a locking bolt connected to said clips whereby upon operation of said bolt the inclined faces of said clips will be caused to simultaneously engage said casing, and clampingly draw said door to said casing in a plane at right angles to the movement of said clips.

3. In an electric controller, a casing, a door for said casing, said door being formed with a peripheral flange which engages said casing in the closed position of said door, said flange being provided with a plurality 90 of spaced gas cooling grooves, as and for the purpose set forth.

4. In an electric controller, a casing, controller shafts extending through said casing, said shafts being provided with grooves whereby flaming gas escaping from the casing at this point is cooled below the ignition point.

In testimony whereof, I affix my signature
HARRY E. CAMPBELL.
